(57) **CLAIM**

What is claimed is the ornamental design for a lighting module locking mechanism, as shown and described.

DESCRIPTION

FIG. 1 is a front, perspective view of a lighting module locking mechanism in accordance with the present design; FIG. 2 is a front view of the lighting module locking mechanism of FIG. 1;

FIG. 3 is a rear view of the lighting module locking mechanism of FIG. 1;

FIG. 4 is a right, side view of the lighting module locking mechanism of FIG. 1, the left side being a mirror image of the right side;

FIG. 5 is a top view of the lighting module locking mechanism of FIG. 1;

FIG. 6 is a bottom view of the lighting module locking mechanism of FIG. 1; and,

FIG. 7 is a perspective view of the lighting module locking mechanism of FIG. 1, with components of a lighting module shown attached to the lighting module locking mechanism of FIG. 1 and in broken lines to illustrate environment for the lighting module locking mechanism of FIG. 1.

The broken lines provided in the drawings form no part of the claimed design.
